ATTORNEY

UNITED STATES PATENT OFFICE.

FREDERICK A. HUBEL, OF DETROIT, MICHIGAN.

CAPSULE-MACHINE.

SPECIFICATION forming part of Letters Patent No. 292,484, dated January 22, 1884.

Application filed July 17, 1883. (No model.)

To all whom it may concern:

Be it known that I, FREDERICK A. HUBEL, of Detroit, in the county of Wayne and State of Michigan, have invented a new and useful Improvement in Machines for Stripping Capsules, of which the following is a specification.

Figure 1 is a vertical section. Fig. 2 is a perspective of a portion of the machine shown in Fig. 1. Fig. 3 is an elevation, partly in section. Fig. 4 is an enlarged view of one of the clamps shown in Fig. 3. Fig. 5 is a detail view, showing one mode of fastening a mold-pin to its plate. Fig. 6 is a horizontal section through Fig. 1.

15 My invention relates to machines for stripping gelatine capsules from the mold-pins on which they are formed; and it consists, mainly, in the combination, with a plate carrying one or more capsule-mold pins so fastened thereto as to be movable laterally, of an inelastic clamp adapted to be closed upon said pin or pins; and, secondly, in certain combinations, hereinafter pointed out in the claims.

25 A represents the frame of the machine. B represents a follower-plate having grooves on its under side to receive and hold the edges of the plate D, and attached to a screw, C, which works in a nut in the top of frame A, and moves plate B. Screw C may be turned 30 by an ordinary hand wheel or lever attached thereto.

35 E, E', and E² represent mold-pins attached to plate D, so that while firmly held by said plate they are capable of lateral motion. Pins E are attached to spring-wires F, which are securely fastened to plate E, and pins E' E² are loosely fastened to plate D, in the manner shown in Fig. 5.

40 G G represent cleats on two opposite sides of frame A, forming ways in which the ends of the jaws J H slide.

45 h j represent cross-straps, h being fastened to the jaws H, and j being fastened to the jaws J. All the cross-straps h are fastened by a cross-piece which is pivoted to the connecting-rod K, and all the cross-straps j are fastened to a cross-piece which is pivoted to the connecting-rod L, as shown in Figs. 1 and 6.

M represents a lever pivoted at O to frame

A, and to this lever are pivoted the connecting-rods K L, so that by moving lever M the jaws J H can be opened or closed.

R represents another form of clamp or jaw, fastened in shaft P, and operated by pinions S and lever Q, as shown and described in Patent No. 268,144, granted to me as assignee of Harrison H. Taylor the 28th November, 1882.

S' represents a method of securing a mold-pin to the mold-carrying plate so that the pin may move laterally, although securely held by the plate.

a a represent recesses cut in the meeting edges of jaws J, H, and R. When the jaws are to be used with mold-pins shaped like E E', where their office is merely to remove the capsule after it has been cut in another machine, the recesses a a may be shallower than half the diameter of the mold-pin, so that each recess will encircle the pin less than one-half its circumference; but when they are to be used with mold-pins like E², where their office is to cut the capsule as they pass the annular groove therein, as well as to remove the capsule, the recesses a should be of such size as to half encircle the pin, so that when the jaws close the pin will be wholly and closely encircled.

The operation of the machine is so obvious that it seems unnecessary to further describe it.

As mold-carrying plates are now made with the pins rigidly fastened thereto, the clamps or jaws used to remove the capsules must have some spring thereto, or be made in some manner so that they may move to adjust themselves to the pins, for it is impossible to set the pins in a number of plates so that they will register exactly with the jaws of one pulling-machine; but by setting the pins on spring-wires or loosely fastening them to the plate I am enabled to use rigid inelastic clamps or jaws, the lateral motion of the pins allowing them to adjust themselves exactly to the jaws.

What I claim as my invention, and desire to secure by Letters Patent, is—

1. The combination, with a plate having laterally-movable capsule-mold pins secured thereto, of a rigid inelastic clamp or jaw

adapted to strip a capsule from a pin, and means for opening and closing the same, substantially as described.

2. A plate for carrying capsule-mold pins, having said pins fastened thereto by spring-wires, substantially as shown and described.

3. In a capsule-pulling machine, the inelastic jaws J H, adapted to strip a capsule from a pin, and means for moving the said jaws, substantially as described.

4. In a capsule-pulling machine, the combi-

nation of a plate carrying one or more yielding mold-pins, having thereon an annular groove and rigid inelastic jaws having recesses therein adapted to be closed upon said pin or pins, substantially as shown and described. 15

FREDERICK A. HUBEL.
